UNITED STATES PATENT OFFICE.

CHARLES A. COMP, OF DETROIT, MICHIGAN, ASSIGNOR TO BUEHL STAMPING COMPANY, OF DETROIT, MICHIGAN, A CORPORATION OF MICHIGAN.

APPARATUS FOR TINNING MILK CANS.

Application filed April 20, 1925. Serial No. 24,707.

The invention relates to machines for rapidly rotating articles such as milk cans and parts used in this manufacture after they have been removed from a bath of molten tin and consists in certain novel features of construction as hereinafter set forth, which renders it particularly adaptable for use in the process of tinning articles described in my copending application Ser. No. 24,706, filed April 20, 1925.

The objects of the invention are first, to provide a machine of simple construction in which the article may be quickly secured before it is materially reduced in temperature; second, to provide means for quickly starting the rotation of the portion of the machine carrying the article; third, to prevent the cooling of the article below the melting point of the tin until after it has been subjected to centrifugal force and fourth, to provide for an automatic stop after a predetermined rotation of the article in order that it may be removed and another piece inserted in the machine. Other objects reside in certain novel features of construction which will be more apparent after consideration of the detailed description of the apparatus as hereinafter set forth.

In the drawings:—

Figure 1 is a side elevation partly in section of a multiple spindle machine;

Figure 2 is an enlarged longitudinal section through one of the spinning units;

Figure 3 is a perspective view of a portion of the machine;

Figure 4 is a plan view;

Figure 5 is a transverse section substantially on the line 5—5 of Figure 4;

Figure 6 is a horizontal section on line 6—6 of Figure 2;

Figure 7 is a sectional elevation of a modified machine;

Figure 8 is a plan view thereof partly in section;

Figure 9 is a transverse section on the line 9—9 of Figure 7.

The machine as illustrated in Figure 1 comprises a frame 10, on which are mounted a series of spinner units 11, 12 and 13 respectively, all of which are driven by a common electric motor 14 mounted at one end of the frame. The frame is preferably built up of structural iron having longitudinal channel members 15 and the transverse angle bars 16. 17 is a horizontal shaft ex-

tending longitudinally of the frame and driven from the motor by the chain drive 18. The shaft is supported in suitable bearings 19 and carries the bevel pinions 20 for transmitting the rotation to the various spinner units. 60

Each of the spinner units comprises a vertical hollow spinner shaft 21 journaled by means of the thrust bearing 22 on a suitable support 23 preferably formed by the upwardly inclined legs 24 rising from the transverse angle bars 16 of the frame. With in the hollow shaft 21 is inserted a stiffening shaft 25 which extends below the lower end of the hollow shaft and carries the rotatable 70 sleeve 26. A bevel gear 27 is keyed to the sleeve 26 and meshes with the bevel pinion 20 while a clutch 28 is mounted above the gear 27 and is longitudinally slidable upon the sleeve 26 as well as being keyed thereto 75 by the key 28^a. At the upper end of the clutch 28 there is a cone-shaped clutch member 29 adapted to engage a cooperating clutch member 30 on the lower end of the shaft 21, the cooperating clutch member be 80 ing provided with the internally coned surface 31. For operating the clutch there is a lever 32 secured to the horizontal shaft 33 and having a bifurcated outer end 34 secured to a collar 35, the latter surrounding the 85 clutch collar 28^a and engaging the annular shoulder 36. The bifurcated outer end 34 is provided with horizontally elongated apertures 37 through which project pins 38, the latter being threadedly secured to the 90 collar 35.

The horizontal shaft 33 extends transversely of the frame 10 and is journaled in bearings 40 upon the longitudinal members 15. For rocking the shaft to raise and lower the clutch a lever 41 is pinned or keyed to the end 42 of the shaft projecting beyond the frame and carries at its outer end a foot pedal 43. The pedal is normally held in raised position by a spring 44 arranged between the same and a bracket 45 projecting from the frame. The shaft 33 also carries a pair of levers 46 to the upper ends of which is secured a brake shoe 47 provided with a segmental surface 48 adapted to engage the outer surface 49 of the clutch member 30. The brake shoe is preferably provided with a friction lining 50 of leather or other suitable material. The levers 32 and 46 are so mounted on the shaft 33 that the 100 105 110

clutch member 29 and the brake shoe 47 are alternately engaged with the spinner shaft 21 by the movement of the foot pedal 43.

It is desirable that the spinner shaft 21 be provided with an arrangement for automatically stopping the same after a predetermined amount of rotation, and for this purpose, I have provided the following mechanism. The pedal 43 is normally urged 10 towards its upper position by a spring 44, but is adapted to be held in lower position by a catch 51 pivotally mounted on the bracket 52 and normally held in engagement with the foot pedal by a spring 53. A rod 15 54 is attached to the catch 51 and has slidably mounted thereon the rack 55. A spring 56 is sleeved upon the outer end of the rod 54 between the rack 55 and a collar 57. 58 is a pinion meshing with the rack 20 55 and loosely mounted upon a shaft 59, which shaft is connected by suitable gearing to the main shaft 17 of the apparatus. For clutching the pinion 58 to the shaft 59 there is a cone clutch comprising the conical 25 member 60 loosely mounted on the shaft 59 and connected to the pinion 58 and the cooperating clutch member 61 non-rotatably secured to the shaft 59. The clutch member 61 is longitudinally slidable upon the shaft 30 58 so as to engage the cooperating member 60 and for controlling this movement there is a lever 62 having a bifurcated arm 63 supporting a collar 64, the latter being engageable with clutch member 61. The lever 35 62 is secured to the transverse shaft 33 and is therefore, actuated by the foot pedal 43.

The operation of the mechanism for controlling the spinner shaft is as follows. When the foot pedal is depressed the clutch 40 member 61 engages the member 60 and causes the pinion 58 to be driven in timed relation with the main shaft 17. At the same time the spinner shaft 21 is started to rotate by the release of the brake shoe 47 45 and the engagement of the clutch member 29 with the clutch member 30. The pinion 58 is driven at a reduced rate of speed because of the reduction gearing between the same and the shaft 17, and since it engages 50 the rack 55 the latter is moved longitudinally on the shaft 54 against the tension of the spring 56. When the spring is compressed to an amount sufficient to overcome the force exerted by the spring 53 the catch 55 55 51 will be withdrawn from engagement with the foot pedal 43 and the latter acting through the levers connected therewith will release the clutch on the spindle and apply the brake shoe 41, thereby quickly stopping 60 the rotation of the spinner shaft. The movement of the foot pedal 43 will also release the clutch 61 so that the pinion once more is loosely mounted on the shaft 58 and rack 55 resumes its original position.

65 For supporting the article to be rotated a

suitable fixture is provided at the upper end of the spinner shaft. This fixture as illustrated in Figures 1 and 2 is designed to support the upper portion of the milk can usually called the milk can breast and comprises an annular casting 65 having the radial plungers 66, the outer ends of which are tapered to a sharp edge 67 in order that the flow of tin will not be impeded thereby. The plungers are resiliently held in engagement with the work by springs 68 sleeved upon the plungers between the shoulders 69 and the casting flanges 70. It will be understood that other fixtures of a similar nature can readily be designed to support on the 70 spinner shaft articles having different contours such for example, as the milk can cover.

75 73 is a cylindrical casing surrounding the spinner unit and provided with a cover 74 hingedly connected thereto. Within this casing and below the article supported on the spinner shaft there is arranged a removable annular container 75 open at its upper end and provided with a conical 80 lower surface 75^a adapted to rest upon the inclined legs 24. The container serves to collect the surplus tin which is thrown from the article by centrifugal force and it may be removed through the top of the casing 95 when it is desired to empty the same.

100 The machine as above described is designed for the rotation of milk can parts after they have been removed from a bath of molten tin and it should be noted that with the machine as designed there are a plurality of spinning units driven by a single motor but each unit is separately controlled. In operation the spinning units are rotated at a suitable speed, e. g. from 105 150 to 300 R. P. M., by means of the variable speed motor 14. The parts when removed from the tin bath are at a temperature of approximately 100° above the melting point of tin and are quickly inserted on 110 the supporting fixture which automatically positions the parts coaxially of the spinner. The cover is then lowered and the pedal 43 depressed so that the article is spun before the tin is congealed upon the surface. 115 After a predetermined rotation the spinner is automatically stopped in the manner above described, the article is removed from the spinner and a new article withdrawn from the tin bath and mounted on the 120 fixture.

125 In Figures 7 to 9 a modified form of machine is shown which is adapted to be used in the process of tinning a completely assembled milk can. With this machine the article instead of being arranged coaxially of the spindle is mounted radially thereof with the open end away from the spinner shaft. Thus, as illustrated, the spinner shaft 76 is mounted similarly to the corresponding shaft 130

21 in the machine first described and is driven and stopped in the same manner. A horizontal plate 77 is secured to the spinner shaft and carries at its outer edges the horizontal angle bars 78 which extend in opposite directions forming supports for the cradles 78^a in which the milk cans are mounted. Each of these cradles comprises a pair of semi-cylindrical metallic straps 75' having the opposite ends thereof secured to the angle bars 78 and provided midway between the ends with inwardly projecting positioning pins 80'. A sheet metal semi-cylindrical lower housing 80 is also secured 10 to said angle bars and carries at its opposite ends the circular sheet metal heads 81 and 82. 83 is a semi-cylindrical upper housing hingedly attached to one of the angle bars as indicated at 84 so as to permit opening of the housing for the insertion and removal of the milk can 85. For positioning the milk can within the housing there are in addition to the pins 80' the sharp pointed strips 79 extending inwardly from the angle bars 78 for engaging the milk can near the bottom thereof and also the round pointed strips 87 for engaging the rounded bead 88. This bead is formed at the junction of the breast of the milk can with the cylindrical lower portion. For absorbing the radial thrust due to the rotation of the device there are the inwardly projecting strips 89 formed with lateral portions 90 adapted to engage the handles 91 of the milk can.

30 With the modified construction as above described, it will be readily apparent that the assembled milk cans may be securely held within a surrounding casing so that the longitudinal axis extends radially of the spinner shaft. Furthermore, the arrangement is such that the milk can can be quickly mounted in the machine after being removed from the tin bath so that it can be subjected to centrifugal action before the temperature 35 drops to the solidification point of the molten tin.

What I claim as my invention is:—

1. In combination, a centrifuge, driving means for said centrifuge, a clutch between said driving means and centrifuge, a lever for actuating said clutch, resilient means for urging said clutch toward one position, a catch for holding said clutch in the other position, a shaft constantly driven by said driving means, and means operable by said shaft for automatically releasing said catch after a predetermined rotation of said centrifuge.

2. In combination, a centrifuge, driving means for said centrifuge, a clutch between said driving means and centrifuge, a lever for actuating said clutch, resilient means for urging said clutch toward disengaged position, a catch for holding said clutch in engaged position, a second clutch operated by

said lever, a pinion driven by said second clutch, and means for releasing said catch operated by said pinion after a predetermined amount of rotation.

3. In a machine of the class described, the combination with a centrifuge and a driving shaft therefor, of a clutch between said centrifuge and driving shaft, a catch for maintaining said clutch engaged, a pinion rotatable in timed relation to said centrifuge, a longitudinally slideable rack engaging said pinion and a resilient connection between said rack and catch adapted to disengage the latter from said clutch after a predetermined rotation of said centrifuge. 80

4. In a machine of the class described the combination with a centrifuge having a driving shaft therefor, of a clutch intermediate said driving shaft and centrifuge, a second shaft geared to said driving shaft, a pinion 85 normally moved on said shaft, a second clutch between said pinion and said second shaft, a lever arranged to engage both of said clutches, common means for holding both of said clutches in engaged position, 90 a rack meshing with said pinion, a resilient connection between said rack and said catch for releasing the latter after a predetermined rotation of said centrifuge.

5. In an apparatus of the class described the combination with a centrifuge and a driving shaft therefor, of a clutch intermediate said driving shaft and centrifuge, a second shaft geared to said driving shaft, a pinion loosely mounted on said second shaft, 100 a second clutch between said pinion and said second shaft, a lever for simultaneously operating both of said clutches to engage the same, a catch engageable with said lever, a rack meshing with said pinion, a resilient connection between said rack and said catch for releasing the latter after a predetermined rotation of said centrifuge, and a 105 brake engageable with said centrifuge and operated by said lever.

6. An apparatus for rotating articles comprising a frame, a vertical spinner shaft journaled thereon, a work holder on said shaft, a driving shaft, a clutch intermediate said driving and spinner shafts, a brake drum on said spinner shaft, a brake shoe, a lever connected to said clutch and said brake shoe, a spring normally holding said lever in a position to seat said brake shoe and to disengage said clutch, a catch engageable 115 with said lever when the latter is in position to engage said clutch, a spring urging said catch toward said lever, a rod attached to said catch, a rack slideable upon said rod, a spring connection between said rack and rod, 120 a pinion engageable with said rack, a shaft driven by said driving shaft, a second clutch between said pinion and said shaft and an arm operated by said lever for actuating said second clutch. 125

7. In a machine of the class described the combination with a centrifuge and a driving shaft for said centrifuge, of a friction clutch intermediate said shaft and centrifuge provided with a friction brake, a second shaft driven by said driving shaft, a pinion loosely mounted on said second shaft, a second clutch for driving said pinion from said second shaft, common means for releasing said brake and engaging both of said clutches, and automatic means operable by said pinion for disengaging both of said clutches and applying said brake.

8. In a machine of the class described, the combination of a rotatable member, a driving shaft, a clutch between the rotatable member and the driving shaft, a second shaft geared to the driving shaft, a pinion, a clutch between the second shaft and the pinion,

common means for engaging both of the clutches and means automatically operable by the said pinion for disengaging both of the said clutches.

9. In combination, a driving shaft, a plurality of centrifuges, a clutch arranged between each centrifuge and the said driving shaft, clutch disengaging means associated with each centrifuge, a second clutch associated with each centrifuge for connecting the said clutch disengaging means with the said driving shaft, and means associated with each centrifuge for actuating both of the said clutches whereby each centrifuge and each clutch disengaging means may be simultaneously connected with the said driving shaft.

In testimony whereof I affix my signature.

CHARLES A. COMP.
